UNITED STATES PATENT OFFICE.

BENJAMIN WEXLER, OF BROOKLYN, NEW YORK, ASSIGNOR TO THE PEELLE COMPANY, OF BROOKLYN, NEW YORK, A CORPORATION OF NEW YORK.

FIREPROOF ELEVATOR-DOOR.

1,342,482.

Specification of Letters Patent.

Patented June 8, 1920.

Application filed October 31, 1918. Serial No. 260,486.

To all whom it may concern:

Be it known that I, BENJAMIN WEXLER, a citizen of the United States, residing at the borough of Brooklyn, in the city of New York, county of Kings, and State of New York, have invented certain new and useful Improvements in Fireproof Elevator-Doors, of which the following is a specification, reference being had therein to the accompanying drawings, which form a part thereof.

My invention relates to fireproof elevator doors, and more particularly to improvements in a type of door known as the truckable type, embodying therein two vertically sliding sections, movable in substantially the same vertical plane, the lower section being arrested by means of suitable stops, while at substantially the level of the sill of the door opening, so as to span the gap between said sill and an elevator car, to facilitate the movement of a load between a floor of the building and said car.

In a door of the type to which my invention relates, the lower door section is subjected to very severe and variable stresses. This is particularly true as to wide doors where the passage of a heavy load across the vertical center of the door has a tendency to warp the entire door structure, however solidly the door may be constructed. Such doors are made of a channeled metal frame, the corners of which are mitered, the panel of the door being made of timbers having a metallic sheathing to prevent fire from attacking the woodwork of the panels. The frames are bolted to the panels and the hanger bar is connected by bolts through the wooden panel and the metal frame thereof. This hanger bar is also used to bring the door to rest at the sill of the opening. The structure above described is that now commonly used.

In a door of the character above referred to, the load stresses in loading and unloading a car, are in part upon the hanger bar, and in part upon the frame of the door. The hanger bar being supported by the stops, is held fairly rigid, although the portion between said stops, under a heavy load, may yield or spring slightly. The frame of the door, however, is supported only by the bolts connecting the hanger bar therewith, and with the wooden panel, so that these stresses as to the door proper, have a tendency to

tilt the door in its entirety, and force the edge of the frame by degrees into the wooden panel, since the sides of the frame are held by the tracks or guides against such movement. It is also difficult in a door of this structure, to prevent skewing of the door by reason of the impossibility of securing a sufficiently rigid connection between the side flanges of the angle iron stock from which the frame is made, at the upper corners thereof.

With these conditions in mind, I have produced a fireproof elevator door of the truckable type, wherein the upper portion of the frame of the lower door section will be so constructed as to possess sufficient rigidity to withstand the severe stresses to which a door of this character is subjected in use. The structure of the door is such that the tendency thereof to tilt under a load, is reduced to a minimum, and the cutting of the frame into the wooden panel is completely eliminated. Furthermore, a tendency of the bolts connecting the hanger bar with other parts of the door structure, to loosen as a result of the racking of the door, is avoided.

The same structure which is used for thus protecting the wooden panel and imparting additional rigidity to the hanger bar, is also used to increase the rigidity of the connection of the top and side bars of the frame at the upper corner of the door section, and thus prevent skewing of the door.

The results above referred to, are secured in a structure requiring substantially no modification of the general design of door now commonly used, being capable of incorporation in the door structure without adding to the thickness of the door, which is a matter of great importance, since the space within which said doors must be mounted, is ordinarily limited.

The invention consists in a fireproof elevator door embodying therein the novel features of construction and combination of parts, hereinafter set forth and described, and more particularly pointed out in the claims hereto appended.

Referring to the drawings, Figure 1 is an elevation of an elevator door embodying my invention, said door being broken on horizontal lines, and condensed;

Fig. 2 is a vertical section through the lower portion of the upper door section,

and the upper portion of the lower door section;

5 Fig. 3 is an elevation of the frame structure and its appurtenances, at one upper corner thereof, before the wooden panel has been mounted therein;

Fig. 4 is a plan view of one upper corner of the lower door section of another embodiment of the invention; and

10 Fig. 5 is a vertical section through the upper portion of the lower door section, and the lower portion of the upper door section of a door embodying the form of the invention shown in Fig. 4.

15 Like letters refer to like parts throughout the several views.

In the embodiment of the invention shown in the drawings, I have illustrated a door composed of an upper section *a* and a lower section *b*, said sections being mounted in the usual manner upon tracks or guides *c* arranged within the shaft upon opposite sides of the door opening. The sections *a* and *b* have movement in opposite directions 20 upon the same vertical plane, the section *b*, when the door is open, coming to rest, with the top thereof on substantially the level of the sill of the door opening. Said sections may be of the same weight, to produce a counterbalanced door structure, or the upper section may be overweighted to produce a self-closing door, or the lower section may be overweighted to produce a self-opening door.

25 Carried by the supporting structure for the tracks or guides *c*, adjacent the sill of the door opening, are the stops *c'*, by means of which the downward movement of the section *b* is arrested, with this section in the proper position in relation to the door sill. The two sections are connected by means of flexible chains or cables *d* passing over suitably arranged pulleys *d'*. The section *a* is composed of a metal frame *a'* inclosing a 30 metal sheathed timber panel *a²* secured thereto by means of the bolts *a³*. The lower bar of the frame *a'* carries the usual astragal and bumper *a⁴*.

The lower section *b* is formed of a frame 35 *b'* of angle iron, similar to the frame *a'*, a sheathed timber panel *b²*, similar to the panel *a²*, inclosed by the frame *b'*, and secured thereto by means of bolts *b³*. The structure of the section *b* differs from that 40 of the section *a* in the construction at the top of the latter section, resulting from the necessity for reinforcing this portion of the door and connecting the hanger bar thereto.

45 In the form of the invention shown, the two door sections are of substantially the same dimensions throughout, and are of substantially the same weight.

50 Referring more particularly to the forms of invention shown in Figs. 1 to 3, to prevent the tilting of the top bar of the frame

b', I provide a metal plate *e* of substantially the same width as the panel *b²*, so as to seat within the frame *b'*, this plate being riveted to one flange of the top bar in the manner shown in Fig. 3, and to one flange of each side bar in a manner to increase the stability of the miter joint at the top corners of the frame. The plate *e* has a depth greater than that of the flange of the top bar, and is provided with two rows of suitable bolt 70 openings *e'*, at suitable intervals of the length thereof. The end opening of the lower row of bolt openings *e'* is in register with a bolt opening in the flange of the side bars of the frame *b'*. 75

80 The timber of the panel *a²* is rabbeted to permit the plate *e* to be inset in this panel, thus avoiding any increase in the thickness of the door.

85 The plate *e* in addition to stiffening the upper part of the frame *b'*, also serves as a stay between the side bars of this frame, the bolts passing through the upper row of bolt openings *e'* and the inturned flanges of the top and side angle bars of the frame, not only imparting the desired rigidity to the frame at this point, but limiting any tilting action under the loads passing over the door to the entire door structure, and thus preventing the mutilation of the panel *b²* by 90 the inturned top flange.

95 The hanger bar, in the form of the invention shown in Figs. 1 to 3, is composed of a T-bar, one top flange of which rests between the panel *b²*, and the truck flange of the frame *b'* extending about the panel. The space between the top flange of the hanger bar *f* and the plate *e*, being protected by the angle bar of the frame, may be closed if desired, by any suitable filler, or may be 100 left vacant. Since the other angle of the top of the T-bar projects beyond the truck flange of the angle frame *b'*, I secure to said T-bar flange, a suitable traction bar *g* flushed with the said truck flange. 110

115 The hanger bar *f* is secured in position with relation to the door section, by means of bolts *h* passing through the upper row of bolt openings *e'* in the inturned flange of the rim angle, the plate *e*, the panel *b²*, and the stem of the T-bar forming the hanger bar *f*, and through bolt openings in a plate *i* parallel with said stem and forming therewith a double hanger bar structure. Other bolts *h* pass through the lower row of bolt 120 openings *e'*, in the plate *e*, the panel *b²*, and said plate *i*, and through both holes in a distance bar *j* of substantially the same thickness as the stem of the hanger bar *f*. In this manner the entire load upon the door 125 frame *b'* is transmitted to the hanger bar *f* through the various bolts *h*, the panel *b²* being relieved of substantially all strains.

130 This condition is further secured as a result of the passage of the end bolts *h* of the

lower row, through the bolt openings e' in the side bars of the frame b' .

Referring now to the form of invention shown in Figs. 4 and 5, this construction is adapted for smaller doors, than that shown in Figs. 1 to 3. In this form of the invention I use an angle bar, one flange k of which is seated in a rabbet of the panel b^2 and the other flange k' of which extends 10 across the top of this panel. The flange k' is of substantially the width of the panel b^2 , while the flange k is of greater width and has each end thereof bent at substantially right angles across the side of said 15 panel, and then at right angles as shown in Fig. 4 at k^2 . The truck flange of the top bar of the frame b' bears upon the flange k' , and the inturned flange of said top bar bears upon the flange k . In this construction the flange k corresponds in function in 20 part with the plate e , and in part with the stem of the T-bar f .

The flange k is riveted to the inturned flange of the top bar and the side bars of 25 the frame b' in the same manner as the plate e the overhang of the flange k' being reinforced with the plate m which is secured in the proper relation thereto by the bolts h in 30 the same manner as the bar j . This plate m extends beyond the panel b^2 and with the ends of the flange k' , form extended hanger bars with which the chains or cables d are connected, and which engage the stops c' .

In both forms of the invention, the 35 hanger bar is so connected with the frame of the door structure as to insure the load stresses applied to the top bar of said frame being transmitted to said hanger bar, so as to cause any movement of the door under 40 such stresses, to be as a unit. In the event of any play in the connections, the plate e or the flange k will afford a sufficiently large bearing surface, to prevent mutilation of the panel b^2 thereby, and will resist any 45 tilting movement of the top bar of the door frame.

It is not my intention to limit the invention to the precise details of construction shown in the accompanying drawings, it being apparent that such may be varied without departing from the spirit and scope of the invention.

Having described the invention, what I claim as new and desire to have protected 55 by Letters Patent is:—

1. A fireproof elevator door composed of two sliding sections oppositely movable in substantially the same vertical plane, the lower of said sections having embodied 60 therein a frame composed of top, bottom and side bars of angle metal, having one flange extending about the edge of said section, and the other flange extending inwardly thereof, a metal sheathed timber 65 panel within said frame, metal reinforce-

ments between the flanges of said top bar and said panel and upon the opposite side of said panel, the reinforcement adjacent said inwardly extending angle of the top bar of the frame being permanently secured thereto and to the inwardly extending flanges of the side bars, and the reinforcements on opposite sides of said panel being bolted together and to said top and said side bars, lateral extensions forming an integral part of said reinforcements projecting beyond said side bars respectively, flexible connections between said extensions and the upper door section, and stops coöperating with said extensions, whereby said lower door section will be sustained adjacent the side of a door opening and the load on the frame of the door will be transmitted to said extensions and said stops, and tilting and rocking of said frame will be prevented. 70 75 80 85

2. A fireproof elevator door composed of two sliding sections oppositely movable in substantially the same vertical plane, the lower of said sections having embodied 90 therein a frame composed of top, bottom and side bars of angle metal, having one flange extending about the edge of said section, and the other flange extending inwardly thereof, a metal sheathed timber 95 panel within said frame, a metal plate permanently secured to the inwardly extending flanges of said top, and said side bars, and disposed between said flange and said panel, a hanger bar having a flange extending parallel with said plate, and a second flange positioned between the edge flange of the frame and the top of the panel, the ends of said hanger bar projecting beyond 100 said frame, bolts passing through the inwardly extending flanges of the top and side bars of the frame, said plate and the parallel flange of said hanger bar, flexible connections between the projecting ends of said hanger bar and the upper door section, and stops coöperating with said extending ends, whereby said lower door section will be sustained adjacent the side of a door opening and the load on the frame of the door will be transmitted to said hanger 105 bar and said stops, and tilting and rocking of said frame will be prevented. 110 115

3. A fireproof elevator door composed of two sliding sections oppositely movable in substantially the same vertical plane, the 120 lower of said sections having embodied therein a frame composed of top, bottom and side bars of angle metal, having one flange extending about the edge of said section, and the other flange extending inwardly 125 thereof, a metal sheathed timber panel within said frame, a metal plate permanently secured to the inwardly extending flanges of said top, and said side bars, and disposed between said flange and said panel, a hanger 130

bar consisting of a T-bar, the stem of which extends parallel with said plate, with one of its top flanges positioned between the edge of said frame, and the top of said panel, and the other top flange thereof projected beyond said frame, the stem of said T-bar extending laterally beyond said frame upon opposite sides of the door section, a reinforcing plate bearing upon, and parallel with, the stem of said T-bar, and engaging the under side of said projected flange, bolts passing through the inwardly extending flanges of the top and side bars of the frame, said plate secured to the frame, the stem of said T-bar and said reinforcing plate, flexible connections between the projecting stem of said T-bar and the upper door section, and stops coöperating with the projected ends of the stem of said hanger bar, whereby said lower door section will be sustained adjacent the side of a door opening and the load on the frame of the door will be transmitted to said hanger bar and said stop, and tilting and rocking of said frame will be prevented.

4. A fireproof elevator door composed of two sliding sections oppositely movable in substantially the same vertical plane, the lower of said sections having embodied therein a frame composed of top, bottom and side bars of angle metal, having one flange extending about the edge of said section, and the other flange extending inwardly thereof, a metal sheathed timber panel within said frame, a metal plate permanently secured to the inwardly extending flanges of said top, and said side bars, and disposed between said flange and said panel, a hanger

bar consisting of a T-bar, the stem of which extends parallel with said plate, with one of its top flanges positioned between the edge of said frame, and the top of said panel, and the other top flange thereof projected beyond said frame, the stem of said T-bar extending laterally beyond said frame upon opposite sides of the door section, a reinforcing plate bearing upon, and parallel with, the stem of said T-bar, and engaging the under side of said projected flange, said last named plate being of the same length as the stem of said T-bar, whereby a double hanger bar structure is afforded, and said plate engaging the projected stem of said T-bar, bolts passing through the inwardly extending flanges of the top and side bars of the frame, said plate secured to the frame, the stem of said T-bar and said reinforcing plate, flexible connections between the projecting stem of said T-bar and the upper door section, and stops coöperating with the projected ends of the stem of said hanger bar, whereby said lower door section will be sustained adjacent the side of a door opening and the load on the frame of the door will be transmitted to said hanger bar and said stop, and tilting and rocking of said frame will be prevented.

In witness whereof I have hereunto affixed my signature, this 21st day of October, 1918, in the presence of two subscribing witnesses.

BENJAMIN WEXLER.
